United States Patent [19]
Morris

[11] Patent Number: Des. 333,226
[45] Date of Patent: ** Feb. 16, 1993

[54] COMBINED TOY HOLDER AND PLAY AREA MODULE

D. 322,495 12/1991 Klok ..... D6/466 X

[75] Inventor: Donald L. Morris, Mountain View, Calif.

Primary Examiner—Alan P. Douglas

Assistant Examiner—Jeffren Asch

Attorney, Agent, or Firm—Edward J. Radlo

[73] Assignee: Magic Edge, Inc., Mountain View, Calif.

[57] CLAIM

The ornamental design for a combined toy holder and play area module, as shown and described.

[**] Term: 14 Years

DESCRIPTION

[21] Appl. No.: 538,193

FIG. 1 is a perspective view of a combined toy holder and play area module showing my new design;

[22] Filed: Jun. 14, 1990

FIG. 2 is a top plan view;

[52] U.S. Cl. D6/466; D3/30.1

FIG. 3 is a right side elevational view, the left side being

[58] Field of Search D6/449, 396, 466, 467, 206/562, 564

a mirror image thereof;

FIG. 4 is a front elevational view;

FIG. 5 is a rear elevational view;

FIG. 6 is a bottom plan view; and,

FIG. 7 is a reduced top plan view thereof, the broken line showings of additional modules being for illustrative purposes only and forming no part of the claimed design.

FIGS. 2-6 have been shown on an enlarged scale with respect to FIG. 1.
